UNITED STATES PATENT OFFICE.

JAMES W. NELSON, OF NEW YORK, N. Y.

APPARATUS FOR GENERATING, CONTROLLING, AND APPLYING HYDRAULIC PRESSURE.

No. 914,170.

Specification of Letters Patent.

Patented March 2, 1909.

Application filed March 12, 1908. Serial No. 420,534.

To all whom it may concern:

Be it known that I, JAMES W. NELSON, a citizen of the United States, and a resident of the city of New York, borough of Brooklyn, county of Kings, and State of New York, have invented certain new and useful Improvements in Apparatus for Generating, Controlling, and Applying Hydraulic Pressure, of which the following is a specification.

10 This invention relates to apparatus for generating and applying hydraulic pressure, with particular reference to devices of exceedingly high power, yet provided with means for rendering available any one of a 15 number of variable lesser pressures, and in which the pressure generating devices are separate from the applying and controlling devices, with flexible connecting conduits therebetween, whereby the apparatus is 20 adapted for use under conditions which would render impracticable, if not impossible, the employment of completely self-contained hydraulic jacks.

It is often desirable and sometimes necessary to divide the applied pressure between 25 two or more separate points, as, for instance, under conditions where it will be impracticable or impossible to locate a jack directly underneath the load to be supported 30 or raised. Furthermore, the employment of two or more rams, each acting upon a member common to all thereof, which member directly receives the weight of the load, will multiply the useful pressure which 35 would be applied by one ram alone by the number of rams employed. It is well known that under the principles of hydrostatics the generated pressure is increased in proportion to the ratio between the areas of the 40 ram and the piston. If the pump is separate from the ram, it will be apparent that when two rams are employed, each suitably connected to the pump, the pressure is not divided, but is multiplied, the area against 45 which pressure is exerted having been increased without increasing the area of the plunger which is operated to generate the pressure.

It is of course essential, under any ordinary 50 conditions which render desirable the employment of two or more rams that the pressures exerted by these rams be equal, otherwise if the pressure of these rams were exerted against the common member which 55 directly received the weight of the load, one end or part of such member would be raised

more rapidly than the other. Therefore, where one or more pressure generating devices are employed, if the generated pressure is to be applied at a plurality of separate points, it is obviously necessary that the pressure applying devices be provided with a common source of supply of the liquid under pressure, in order to equalize the applied pressures.

In addition to providing a device for the generation and application of exceedingly high pressures, the present invention contemplates a device which, while employing the usual type of reciprocating plungers to 70 generate the pressure, will make such generation continuous and uniform instead of intermittent. Such continuous generation and application of pressure is not infrequently desired, and it will be apparent that 75 where reciprocating plungers are employed at least three plungers, or three series of pistons the pistons in each series being actuated by the same reciprocating rod, will be necessary. If the pumps are power-driven, 80 as is more particularly contemplated in the present invention, they may be coupled to a main driving shaft by cranks equidistantly spaced apart on said shaft with reference to the circumference thereof—that 85 is, separated by arcs of 120° . In this manner, not only will there at all times be a piston-rod which is being actuated on its downward and useful stroke, but the relation of parts is such that with the conduits 90 from the pumps uniting in a common pressure distributing chamber, the generation and application of pressure will be substantially continuously uniform.

The present invention further contemplates the employment, in connection with a plurality of separate pumps and a plurality of separate pressure applying devices, a member interposed between said pumps and said applying devices, and located in 100 proximity to the latter, whereby the operator stationed at such member may note the progress and effect of the work, in which member the conduits from the pumps unite to equalize the applied pressures and which 105 member is provided with means for the control of the pumping operations, whereby one or more of said pumps may be rendered effectively inoperative to reduce the total generated pressure without ceasing the 110 pumping operations, and with means for finally relieving the applied pressures when

it is desired to remove or readjust the apparatus.

My invention will be more readily understood by reference to the accompanying drawings forming a part of this specification, in which—

Figure 1 is a diagrammatic view, partly in section, of a complete apparatus embodying my invention; Fig. 2 is an enlarged sectional elevation of the separate controlling member; Fig. 3 is a section taken substantially on the line 3—3 of Fig. 2; Fig. 4 is a section taken substantially on the line 4—4 of Fig. 2, and Fig. 5 is a transverse section 10 through the lower part of the cylinder shown 15 in Fig. 2.

Referring now to the drawings in detail, numerals 11, 12, 13 refer to hydraulic pumps which for the purpose of this description are shown as of the multiple plunger type. These pumps need not necessarily be of the same size or capacity, as it will be apparent that a wider range of degrees of pressure which may be generated 20 and applied may be secured through the employment of pumps of different sizes and capacities. Where a continuously uniform generation of pressure is desired, however, and under any ordinary conditions, these 25 pumps may be as shown, substantially identical.

The pump-block of the pump 11 is provided with a central pump-bore comprising an upper portion 14 of relatively larger diameter and a lower portion 15 of relatively 30 smaller diameter. Extending into this pump bore is the piston-rod 16 carrying the piston 17 fitting and adapted to reciprocate in the portion 14 of the pump bore. An extension 40 of the piston-rod projects from the piston 17 and has mounted on the end thereof the piston 19 fitting and adapted to reciprocate in the portion 15 of the said pump-bore. The piston-rod 16 may be reciprocated by means 45 of the usual manually-operated pump-lever, but for the purposes of this description, and in order to avail myself of all of the advantages of the type of apparatus which I am about to describe, I prefer to provide a suitably journaled rotating shaft 20, driven by a 50 pulley 21 from any convenient source of power, and provided with the double-crank 22, interposed between which and the end of the piston-rod 16 is the connecting link 23. 55 This shaft 20 is common to all of the pumps, the piston-rod 24 of the pump 12 being similarly connected to the crank 25 by means of the link 26, and the piston-rod 27 of the pump 13 being similarly connected to the 60 crank 28 by means of the link 29. These cranks 22, 25 and 28 are equidistantly disposed with reference to the circumference of the shaft 20, said cranks being therefore circumferentially separated by arcs of 120°. It 65 will be seen that such construction and rela-

tive location insures at all times a downward stroke of some one of the three piston- rods and, therefore, a continuous delivery of liquid under pressure to the common pressure distributing chamber hereinafter described. It is understood, of course, that the pumps 12 and 13 are provided with pump-bores of varying diameters corresponding with the one described in connection with the pump 11 and similarly contain 70 two pistons reciprocating in each of said bores.

In the pump 11, a lateral duct 30 is provided leading from the bottom of the larger portion 14 of the pump-bore below the piston 17 to and through the coupling 31 which is suitably secured to the pump-block and to the end of the preferably flexible pipe 32. A similar duct 33 leads from the bottom of the smaller portion 15 of the pump-bore to 80 and through the coupling 34 at the end of the pipe 35, which coupling is similarly secured to the pump block 11 and connects said pipe 35 thereto. In the pump 12, a duct corresponding to the duct 30 leads to 85 and through the coupling 36 which connects the end of the pipe 37 to said pump-block, and with a duct which corresponds to the duct 33 leading to and through the coupling 38 to the pipe 39. Corresponding ducts are 90 provided in the pump block 13, the upper leading to and through the coupling 40 at the end of the pipe 41 and the lower leading to and through the coupling 42 at the end of the pipe 43.

The pump and pressure valves and the means for their control are provided in a separate member 44, which is preferably of substantially cylindrical shape and mounted upon a heavy base or standard 45 which insures the body or member 44 being held during operations in a substantially vertical position. The lower end of the member 44 is provided with a central bore 46, and the other end thereof with three relatively 100 smaller bores extending from the top of said body to the upper end of the bore 46. These three smaller bores are identical in size, shape and relative location. Referring first to one thereof, it will be seen that the same is 105 of varying diameters, the portion 47 thereof, which leads into the bore 46, being of smallest diameter, the diameter being increased at 48 to provide a seat for the valve 49, which is downwardly seating and which is 110 provided with a stem 50 which projects downwardly and extends into the bore 46. At 51, the portion 52 of said bore is again increased in diameter to provide a seat for the valve 53, which has a downwardly projecting stem 54 extending nearly but under normal conditions not quite to the valve 49. In order that this bore shall not be increased in diameter beyond practical limits, I again 115 reduce the effective diameter thereof by 120

placing within the portion 55 of said bore the removable cylindrical plug 56, the top of which provides a seat for the valve 57 which has a downwardly projecting stem 58 extending nearly but under normal conditions not quite to the valve 53. The top of said bore is closed and sealed by means of the screw-plug 59 which provides a chamber 60 above the valve 57 in which a spring 61 is in compression to yieldingly seat said valve.

The other valve-bore shown in Fig. 2, comprises the corresponding lower and smaller portion 62 which at 63 is increased in diameter to provide a seat for the valve 64 which has a stem 65 projecting downwardly and extending into a bore 66. The portion 66 of said bore, thus increased in diameter, is at 67 again increased in diameter to provide a seat for the valve 68 which has a downwardly-projecting stem 69 extending nearly but under normal conditions not quite to the valve 64. The portion 70 of said bore, thus again increased in diameter, is correspondingly provided with the movable cylindrical plug 71, the top of which provides a seat for the valve 72 which has a downwardly-projecting stem 73 extending nearly but under normal conditions not quite to the valve 68. The upper end of this bore is similarly closed and sealed by means of the screw-plug 74 which provides the chamber 75 above the valve 72, and in said chamber is correspondingly placed a spring 76 tending to seat said valve.

The third valve-bore is located as indicated in Figs. 3 and 4. This bore, being identical in all respects to the two valve-bores just described and containing an equal number and a similar arrangement of valves, is not shown in the drawings other than as illustrated in Figs. 3 and 4. This third valve-bore is similarly closed and sealed at its upper end to provide the chamber 77, the chambers 60 and 75 being open to each other through the duct 78 which is, in turn, open to the chamber 77 through the duct 79. It will thus be seen that the pressures in the chambers 60, 75 and 77 are at all times equal.

The pipe 32 from the upper and larger pump-chamber in the pump 11, leads through a suitable coupling to the duct 80 in the radially disposed arm 81, which duct communicates with the portion 52 of one of the valve-bores, between the valves 49 and 53. The pipe 35 from the lower and smaller pump-chamber in the pump 11 leads to the duct 82 in the correspondingly located arm 83 above the arm 81, which duct 82 leads to the portion 55 of said valve-bore between the valves 53 and 57.

The pipe 37 from the upper and larger pump-chamber in the pump 12, leads to the duct 84 in the arm 85, which duct 84 is open to the portion 66 of the second valve-bore between the valves 64 and 68. The pipe 39 from the lower and smaller pump chamber in

the pump 12, leads to the duct 86 in the arm 87 above the arm 85, said duct 86 leading to the portion 70 of said valve-bore above the valve 68 and below the valve 72. Similarly, the pipe 43 from the lower and smaller pump-chamber in the pump 13, leads to the duct 88 in the arm 89, said duct 88 being open in a precisely similar manner to the third valve-bore between the highest and the intermediate valves in said bore. The pipe 41 from the upper and larger pump-chamber in the pump 13, leads to a duct in a corresponding arm located below the arm 89, said duct being open to the third valve-bore between the lowest and the intermediate valves in said bore.

From the chamber 60 at the top of the first-described valve-bore, leads a duct 90 through an arm 91 to which is secured the coupling 92 at the end of the pipe 93, and from the chamber 75 at the top of the second valve-bore leads the duct 94 to and through the arm 95 upon which is secured the coupling 96 at the end of the pipe 97. The latter leads through the coupling 98 and the duct 99 in the ram-cylinder 100 to the pressure chamber 101 below the ram 102. The pipe 93 leads through the coupling 103 and a duct which corresponds to the duct 99, to the pressure chamber in the ram-cylinder 104 below the ram 105.

Fitting and adapted to reciprocate in the bore 46 of the member 44, is the push tube 106, the lower end of which is preferably provided with the inturned flange 107 between 100 which and the top of said bore a spring 108 is in compression to yieldingly force said tube 106 to its lowermost position. The body 44 is provided with a lateral bore leading to the bottom of the bore 46, said lateral bore being 105 interiorly screw-threaded for the reception of the screw-plug 108 in which is journaled the shaft 109. Mounted on the inner end of this shaft, and in co-operative positional relation to the bottom of the tube 106 is the cam 110. I prefer to provide the outer end of the shaft 109 with a head 111 to which may be suitably secured the end of the operating lever 112 by which the shaft 109 may be rotated. The cam 110 is of such configuration and so 115 mounted that under normal conditions the tube 106 resting thereagainst is noninterferent with automatic operations of any of the lower valves in the three valve-bores—that is to say, the top of said tube does not contact with the lower end of any one of the lower valve-stems. Upon rotation of said shaft 109, however, by means of the lever 112, said cam 110 will operate to raise the tube 106 against the action of the spring 108 120 and cause the top of said tube to impinge against the stem 65 of the valve 64 and positively hold the latter off its seat without, however, interfering with automatic operation of either of the two remaining lower 125 valves.

valves in the other valve-bores. Further upward movement of said tube 106, as rotation of said shaft 109 is continued, will, owing to the slight difference in the length of the valve stems, next unseat and hold off its seat in a similar manner the valve 49; next, in a similar manner, the lowermost valve in the third valve-bore. Continued upward movement of said tube 106, will next cause the unseated lower valves to successively impinge against the lower ends of the stems of the valves next above the same and unseat these three intermediate valves in correspondingly consecutive order. Still further continued upward movement of said tube 106, will next, in correspondingly consecutive order, unseat the three upper valves in the valve-bores and thus open and hold open passages from the chambers 60, 75 and 77 to the bore 46. From this bore 46 leads a lateral duct 113 to and through the nipple 114 which is provided for the reception of the preferably rubber or other flexible hose or pipe 115 which leads to any suitable or convenient source of liquid supply. This source of supply may be in the form of a tank or barrel, possibly sufficiently elevated that the force of gravity will tend to assist the pumps in drawing the liquid therefrom, and, under any circumstances, said source of supply is always in open communication with the bore 46 in the member 44, the aperture 116 at the bottom of the push-tube 106 permitting the flow upwardly through said bore 46 to the three valve-bores.

It will now be apparent that under normal conditions, with the various parts in the positions indicated in the drawings, and referring first to operations of the pump 11, upon the up-stroke of the pistons in said pump, partial vacuums will be created in the chambers 14 and 15 below said pistons. The unequal pressures thus created will cause the valves 49 and 53 to be unseated and a flow of liquid directed from the source of supply to the bore 46 and thence upwardly through the portion 47 of the valve-bore past the valve 49, where it is divided, a part thereof flowing through the duct 80 and filling the chamber 14 below the upper piston in the pump 11, and a part continuing upwardly through the portion 52 of said bore, past the valve 53, and thence through the duct 82 and the pipe 35 to the chamber 15 below the smaller piston in said pump. Upon the downstroke of said pistons, the valve 49 will be seated under excess of pressure above the same, and the liquid from both pump chambers will be directed upwardly through the portion 55 of the valve bore, past the valve 57, which is unseated, and into the chamber 60 at the upper end of said bore. As has been explained, this chamber 60 is open to the chamber 75 through the duct 78, and, therefore, the pressure generated by the pump 11 will be equally distributed

between the two ram-chambers through 65 the conduits 93 and 97.

In a precisely similar manner, the partial vacuums resulting from the up-stroke of the pistons in the pump 12 will cause unequal pressures which will result in the unseating of 70 the valves 64 and 68 and a flow of liquid from said source of supply through the ducts 84 and 86 and the pipes 37 and 39 to said pump-chambers. The down-stroke of said pistons will seat the valve 64 and direct the liquid in a 75 similar manner past the valve 72 and into the chamber 75, from whence its application is similarly equalized between the two or more pressure-applying devices. Similarly, up-stroke of the pistons in the pump 13 will fill 80 the pump-chambers from the source of supply, and the down-stroke of said pistons will in an identical manner direct the flow from said pump to the chamber 77 at the top of the third valve-bore, from whence the liquid 85 is directed through the ducts 75 and 78 to the chambers 60 and 75 and thence to the ultimate pressure chambers.

With all of the pumps effectively operating, it will be apparent that a maximum volume 90 of liquid will be forced to the ram-chambers, as is desirable in order to rapidly raise the rams to the point where they receive the full weight of the load. Whenever it becomes desirable to sacrifice speed for power, as may 95 be done by decreasing the area of the surfaces through which the power is applied, the lever 112 may be turned sufficiently to rotate the cam 110 through an arc sufficient to raise the tube 106 to the point where the latter has unseated the lowest valve in each of the three valve bores, in the manner hereinbefore described, without interfering with automatic action of any of the remaining valves. Referring first to the effect of this operation 100 upon the pump 11, it will now be apparent that with the valve 49 held off its seat, an open passage is provided between the pump-chamber underneath the larger piston in said pump and the source of supply. Therefore, upon 110 the down-stroke of the pistons the liquid under the pressure of the larger piston, instead of being directed upwardly past the valves 53 and 57, will follow the path of least resistance and return past the unseated valve 49, 115 through the chamber 46, and back to the source of supply. Similarly, with the valve 64 unseated, an open passage has been provided from the pump-chamber underneath the larger piston in the pump 12 to the source 120 of supply, and upon the down-stroke of the pistons in said pump the liquid in said larger pump-chamber will, instead of being upwardly directed past the valves 68 and 72, follow the path of least resistance and return 125 in a similar manner to the source of supply. Similarly, with the lowest valve in the third valve-bore unseated the larger piston in the

5 pump 13 has been rendered inoperative, and it will therefore be apparent that the smaller pistons alone in all of the three pumps are effectively operative and the generated pressure 70 sure materially increased under the principles of hydrostatics, with such generation still continuous and uniform.

10 While it is not conceived that any ordinary conditions could render desirable the successive unseating of the lower valves in the valve-bores, it will nevertheless be seen that should it be desired for any purpose to render effectively inoperative the larger piston in any one of the pumps alone, this may be done 15 by turning the lever 112 through an arc sufficient to operate through the cam 110 to unseat the valve 64 without interfering with automatic action of any of the remaining lower valves. In this manner, the larger 20 piston in the pump 12 has alone been rendered inoperative, and the larger piston in the pump 11 may also be rendered inoperative by continuing rotating of said lever to the point where the valve 49 is unseated 25 without interfering with automatic action of the lower valve in the third valve-bore.

25 The lengths of the valve stems 54 and 69 and the corresponding valve-stem in the third valve bore, are so proportioned that 30 continued upward movement of the tube 106, after the lowest valves have been unseated, will first unseat the valve 68, next the valve 53, and next the intermediate valve in the third valve-bore. In this manner, in addition 35 to the larger pistons in the three pumps, the smaller pistons therein may be successively rendered effectively inoperative, whereby the speed with which the rams are being raised may be reduced until all of the pumps 40 are rendered inoperative, although the pressure in the ram chambers remains the same. Finally, a continuance of the upward movement of the tube 106 will next operate through the stem 73 to unseat the valve 72; 45 next, through the stem 58, unseat the valve 57, and, last, in a similar manner, unseat the highest valve in the third valve-bore. This last operation is designed to effect the relief of the pressures within the ram chambers, 50 when it is desired to lower the rams for the removal or the readjustment of the devices. It will be apparent that with the tremendous pressures which will be generated within the ram chambers the final pressure 55 valves are obviously unseated with considerable difficulty. It will be appreciated that one of these three valves may be unseated with less effort than two or three thereof, and for this purpose the stems of the 60 uppermost valves are correspondingly proportioned in length, whereby one of said valves only is first unseated. The instant one of said valves is raised even the slightest extent off its seat, the pressures on both 65 sides thereof become equalized and it may

be further unseated without difficulty. Once the excessive pressures in the ram chamber is relieved, the remaining valves may be easily unseated for the purpose of hastening the operation of lowering through the provision of a plurality of passages back to the source of supply. 70

Many modifications of minor details of my improved apparatus for generating, controlling and applying hydraulic pressure will 75 doubtless readily suggest themselves to those skilled in the art to which it appertains, and I therefore do not desire to limit my invention to the specific construction herein shown and described. 80

I claim as new and desire to secure by Letters Patent:

1. In combination, a plurality of at least three separate mechanisms for generating hydraulic pressure, each thereof comprising a 85 plurality of pressure generating means, means for applying the generated pressure, and means for rendering effectively inoperative one pressure generator in each of said mechanisms, said means being further operable 90 to render effectively inoperative more than one generator in each of said mechanisms.

2. In combination, a plurality of at least three separate mechanisms for generating hydraulic pressure, each thereof comprising 95 a plurality of pressure generating means, means for applying the generated pressure, and means for rendering effectively inoperative one pressure generator in each of said mechanisms, said means being further operable 100 to render effectively inoperative all of the pressure generating means.

3. In combination, a plurality of at least three separate mechanisms for generating hydraulic pressure, each thereof comprising 105 a plurality of pressure generating means, means for applying the generated pressures, and means for rendering effectively inoperative one pressure generator in each of said mechanisms, said means being further operable 110 to render effectively inoperative all of the pressure generating means and finally to relieve the applied pressures.

4. In combination, a plurality of at least three separate mechanisms for generating 115 hydraulic pressure, each thereof comprising a plurality of individually operative pressure generating means, a pressure-distributing chamber common to all of said generating means, means for actuating said mechanisms to continuously force liquid into said chamber, and means for varying the generated pressure and for rendering said generating mechanisms inoperative. 120

5. In combination, a plurality of at least 125 three separate mechanisms for generating hydraulic pressure, each thereof comprising a plurality of individually operative pressure generating means, a pressure-distributing chamber common to all of said generat- 130

ing means, means for actuating said mechanisms to continuously force liquid into said chamber, and means for varying the generated pressure, for rendering all of said generating mechanisms inoperative, and for relieving the applied pressure.

6. In combination, a plurality of at least three separate mechanisms for generating hydraulic pressure, each thereof comprising 10 a plurality of individually operative pressure generating means, a pressure-distributing chamber common to all of said generating means, means for actuating said mechanisms to continuously force liquid into said 15 chamber, and means for rendering effectively inoperative in alternate and consecutive order all of said generating means.

7. In combination, a plurality of at least 20 three separate mechanisms for generating hydraulic pressure, each thereof comprising a plurality of individually operative pressure generating means, a pressure-distributing chamber common to all of said generating means, means for actuating said mechanisms to continuously force liquid into said 25 chamber, and means for rendering effectively inoperative in alternate and consecutive order all of said generating means, said means being further operable to relieve the 30 applied pressures.

8. In combination, a plurality of at least 35 three multiple-plunger pumps, a common pressure-distributing chamber and means for directing the flow from all of the pump chambers thereto, means for actuating said pumps to continuously force liquid to said chamber, and means common to all of said 40 pumps for rendering ineffective the operations of one or more of the plungers in said pumps.

9. In combination, a plurality of at least 45 three multiple-plunger pumps, a common pressure-distributing chamber and means for directing the flow from all of the pump chambers thereto, means for actuating said pumps to continuously force liquid to said chamber, and means common to all of said 50 pumps for rendering effectively inoperative one or more of the plungers and one or more of said pumps.

10. In combination, a plurality of at least 55 three multiple-plunger pumps, a common pressure-distributing chamber and means for directing the flow from all of the pump chambers thereto, means for actuating said pumps to continuously force liquid to said chamber, and means common to all of said 60 pumps for rendering effectively inoperative one or more of the plungers in each pump and one or more of said pumps.

11. In combination, a plurality of at least 65 three multiple-plunger pumps having common actuating means and operating with successively effective strokes to continu-

distributing chamber, means separate therefrom for applying the generated pressure, and means common to all of said pumps for rendering ineffective the operations of one or more of said plungers.

12. In combination, a plurality of at least 70 three multiple-plunger pumps having common actuating means and operating with successively effective strokes to continuously force liquid to a common pressure-distributing chamber, means separate therefrom for applying the generated pressure, and means common to all of said pumps for rendering ineffective one or more of the plungers and one or more of said pumps.

13. In combination, a plurality of at least 75 three multiple-plunger pumps having common actuating means and operating with successively effective strokes to continuously force liquid to a common pressure-distributing chamber, means separate therefrom for applying the generated pressure, and means common to all of said pumps for rendering ineffective one or more of the plungers in each 80 pump and one or more of said pumps.

14. In combination, a plurality of at least 85 three multiple-plunger pumps having common actuating means and operating with successively effective strokes to continuously force liquid to a common pressure-distributing chamber, means separate therefrom for applying the generated pressure, and means common to all of said pumps for rendering ineffective the operations of one or more of 90 said plungers and for finally relieving the 100 applied pressures.

15. In combination, a plurality of at least 95 three multiple-plunger pumps having common actuating means and operating with successively effective strokes to continuously force 105 liquid to a common pressure - distributing chamber, means separate therefrom for applying the generated pressure, and means for consecutively rendering effectively inoperative the plungers in all of said pumps and for 110 finally relieving the applied pressure.

16. In combination, a plurality of at least 115 three successively-operating multiple-plunger pumps, a device separate therefrom for applying the generated pressure, a flexible conduit from each pump-chamber and to said applying device, said conduits uniting in a member which is provided with means for rendering the plungers effectively inoperative in consecutive alternation.

17. In combination, a plurality of at least 120 three successively-operating multiple-plunger pumps, a device separate therefrom for applying the generated pressure, a flexible conduit from each pump-chamber and to said applying device, said conduits uniting in a member which is provided with means for rendering one plunger in each of said pumps inoperative.

18. In combination, a plurality of at least 130

three successively-operating multiple-plunger pumps, a device separate therefrom for applying the generated pressure, a flexible conduit from each pump-chamber and to said applying device, said conduits uniting in a member which is provided with means for rendering effectively inoperative one or more of the plungers in each pump and one or more of said pumps.

10 19. In combination, a plurality of at least three successively-operating multiple-plunger pumps, a device separate therefrom for applying the generated pressure, a flexible conduit from each pump-chamber and to said applying device, said conduits uniting in a member which is provided with means for rendering effectively inoperative one plunger in each of said pumps, said means being further operable to render effectively inoperative more than one plunger in each of said pumps.

20 20. In combination, a plurality of at least three successively-operating multiple-plunger pumps, a device separate therefrom for applying the generated pressure, a flexible conduit from each pump-chamber and to said applying device, said conduits uniting in a member which is provided with means for rendering effectively inoperative one plunger in each of said pumps, said means being further operable to render all of said pumps effectively inoperative.

25 21. In combination, a plurality of at least three successively-operating multiple-plunger pumps, a device separate therefrom for applying the generated pressure, a flexible conduit from each pump-chamber and to said applying device, said conduits uniting in a member which is provided with means for rendering effectively inoperative one plunger in each of said pumps, for rendering all of said pumps inoperative, and for finally relieving the applied pressures.

30 22. In combination, a plurality of at least three successively operative multiple-plunger pumps, means for applying the generated pressure, a suitable conduit from each pump-chamber and to said applying means, the conduits from the pump-chambers in each pump uniting in a common passage and said passages uniting in a common pressure-distributing chamber, suitable pump and pressure valves in said passages, and means for controlling said valves to render one plunger in each of said pumps inoperative.

35 23. In combination, a plurality of at least three successively operative multiple-plunger pumps, means for applying the generated pressures, a suitable conduit from each pump-chamber and to said applying means, the conduits from the pump-chambers in each pump uniting in a common passage and said passage uniting in a common pressure-distributing chamber, suitable pump and pressure valves in said passages, and means

for controlling said valves to render one plunger in each of said pumps inoperative, said means being further operable to render more than one plunger in each pump inoperative.

70

24. In combination, a plurality of at least three successively operative multiple-plunger pumps, means for applying the generated pressures, a suitable conduit from each pump-chamber and to said applying means, the conduits from the pump-chambers in each pump uniting in a common passage and said passages uniting in a common pressure-distributing chamber, suitable pump and pressure valves in said passages, and means for controlling said valves to render one plunger in each of said pumps inoperative, to render all plungers inoperative, and to relieve the applied pressures.

25. In combination, a plurality of at least three successively operative multiple-plunger pumps, means for applying the generated pressures, a suitable conduit from each pump-chamber and to said applying means, the conduits from the pump-chambers in each pump uniting in a common passage and said passages uniting in a common pressure-distributing chamber, suitable pump and pressure valves in said passages, and means common to all of said valves for unseating the same in consecutive alternation.

26. In combination, a plurality of at least three successively operative double-plunger pumps, means for applying the generated pressures, a suitable conduit from each pump-chamber and to said applying means, the conduits from the pump-chambers in each pump uniting in a common passage and said passages uniting in a common pressure-distributing chamber, suitable pump and pressure valves in said passages, and means for controlling said valves to render one plunger in each of said pumps inoperative.

27. In combination, a plurality of at least three successively operative multiple-plunger pumps, means for applying the generated pressures, a suitable conduit from each pump-chamber and to said applying means, the conduits from the pump-chambers in each pump uniting in a common passage and said passages uniting in a common pressure-distributing chamber, a series of valves for one pump in each of said passages, one checking back-flow from one pump-chamber, another checking back-flow from the other pump-chamber and a third checking back-flow from the pressure-distributing chamber, and means common to the valves in all of said passages for unseating corresponding valves in said series in consecutive order.

28. In combination, a plurality of at least three successively-operative multiple-plunger pumps, means for applying the generated pressures, a suitable conduit from each pump-chamber and to said applying means,

130

the conduits from the pump-chambers in each pump uniting in a common passage and said passages uniting in a common pressure-distributing chamber, a series of valves for 5 one pump in each of said passages, one checking back-flow from one pump-chamber, another checking back-flow from the other pump-chamber and a third checking back-

flow from the pressure-distributing chamber, and means common to all of said valves to 10 unseat the same in alternate and consecutive order.
